UNITED STATES PATENT OFFICE.

EVAN HARTER, OF DETROIT, MICHIGAN, ASSIGNOR TO DETROIT STOVE WORKS, OF DETROIT, MICHIGAN, A CORPORATION OF MICHIGAN.

STOVE-FRAME.

1,217,939.

Specification of Letters Patent.

Patented Mar. 6, 1917.

Application filed June 10, 1916. Serial No. 102,844.

To all whom it may concern:

Be it known that I, EVAN HARTER, a citizen of the United States of America, residing at Detroit, in the county of Wayne 5 and State of Michigan, have invented certain new and useful Improvements in Stove-Frames, of which the following is a specification, reference being had therein to the accompanying drawings.

10 The invention relates to stove frames, and it is the object of the invention to form the structure from sheet-metal, as hereinafter set forth.

In the drawings:

15 Figure 1 is a plan view of the frame; Fig. 2 is a sectional perspective view thereof; Fig. 3 is a plan view, showing the manner of cutting the bar to form a corner; and 20 Fig. 4 is a section on line $\alpha-\alpha$ Fig. 2, showing the manner of securing the corner.

In the present state of the art it is usual 25 to form the supporting base frames for sheet-metal stoves of angle bars or other rolled bars of structural shape. As the frames are of annular form and usually rectangular, it is necessary to make special provision for the forming of the corners, by providing either corner brackets for joining 30 separate sides or other means. I have simplified the construction by forming a bar of structural shape from folded sheet-metal, and by forming a frame of this bar without the necessity of additional corner 35 brackets.

In detail, I preferably form the bar of a 40 T-section, having the head portion of the T arranged in a vertical plane and the stem portion extending laterally. This T is formed by folding sheet-metal, with an outer 45 ply A, returnbent portions B and B' and outwardly-extending parallel portions C and C', with a returnbend or seam D for joining their outer ends. To form the 50 frame, the stem-portion of the T formed by the parallel plies C and C' is gored or cut away at the corners, as indicated at E Fig.

3. The vertical or head portion A is then bent to form the angle, and the plies C and C' of the stem are telescopically engaged 50 with each other so as to overlap, as shown in Fig. 4. The rivet F or other securing device may then be engaged with the overlapping plies to hold the same from displacement.

With the construction as described, the laterally-extending portion of the bar will constitute a seat or support for the superstructure, and the overlapping portions of the sheet-metal which are secured to each other greatly strengthen the corners. This overlapping does not produce any objectionable offset in the plane of support for the superstructure, as the gage of the single 60 ply of sheet-metal is comparatively slight; and furthermore, if desired, the metal may be slightly deflected to bring the upper plies of adjacent sides into exactly the same plane, as indicated in Fig. 4.

What I claim as my invention is:

1. In a stove, a supporting frame comprising a bar of structural shape, formed of folded plies of sheet-metal, the laterally-extending portion of said bar being cut at the corners and the plies thereof overlapped.

2. In a stove, a supporting frame comprising a T-bar formed of folded plies of sheet-metal, the head portion of the T extending in a vertical plane and the stem portion extending laterally, said stem portion being cut at the corners of the frame and having the plies thereof overlapped.

3. In a stove, a supporting frame comprising a T-bar formed of folded plies of sheet-metal, the head portion of the T being arranged in a vertical plane and the stem portion extending laterally, said stem portion being cut to form a corner, with the plies thereof overlapped, and securing means for said overlapping plies.

4. In a stove, a supporting frame comprising a T-bar formed of folded plies of sheet-metal, the head portion of the T being arranged in a vertical plane and being

formed from a center of the blank which is returnbent at opposite edges thereof, and the stem portion of the T extending laterally and formed by parallel portions of the blank, seamed together at their outer edges, said stem portion being cut to permit of folding the head to form a corner, and the plies of the web being interengaged to form

an overlap, and means for securing said plies to each other.

In testimony whereof I affix my signature.

EVAN HARTER.
